(57) CLAIM

The ornamental design for a plant support, as shown and described.

DESCRIPTION

FIG. 1 is an exploded perspective view of a plant support, showing the new design with a basket portion separated from a base portion, only one of the four basket portions being shown for clarity of illustration;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.
